SPRAYING MACHINE FOR CAN ENDS AND SIMILAR ARTICLES.

APPLICATION FILED JUNE 3, 1912.

1,281,349.

Patented Oct. 15, 1918.

3 SHEETS—SHEET 3.

UNITED STATES PATENT OFFICE.

CHARLES W. GRAHAM, OF NEW YORK, N. Y., ASSIGNOR TO AMERICAN CAN COMPANY,
OF NEW YORK, N. Y., A CORPORATION OF NEW JERSEY.

SPRAYING-MACHINE FOR CAN ENDS AND SIMILAR ARTICLES.

1,281,349.

Specification of Letters Patent. Patented Oct. 15, 1918.

Application filed June 3, 1912. Serial No. 701,132.

To all whom it may concern:

Be it known that I, CHARLES W. GRAHAM, a citizen of the United States, residing in New York, in the county of New York and 5 State of New York, have invented a new and useful Improvement in Spraying-Machines for Can Ends and Similar Articles, of which the following is a specification.

This invention relates to improvements 10 in machines for automatically coating articles, and relates more particularly to that class of machines for applying or spraying a coating of lacquer or other liquid to can ends or other articles, although, as will be 15 evident to those skilled in the art, the machine may be adapted for many other uses.

The object of the invention is to provide a machine capable of automatically treating can heads or other articles at a high rate 20 of speed, and in which a single spraying device is used for coating articles on two conveyers, thereby obtaining the maximum use and efficiency from the sprayer and obviating the necessity for duplicating this 25 part of the mechanism.

Another object of the invention is to so arrange the elements that a station is provided between the point where the articles are supplied or fed to the machine and the 30 place where the articles are coated or treated, whereby an operator may observe the articles after they have been placed on the conveyer and inspect the same to see if they have been properly placed on the conveyer.

My invention furthermore consists in the improvements in the parts and devices and in the novel combinations of parts and devices herein shown, described or claimed.

One form of the invention which I have 40 shown as embodying my improvements, consists of a framework adapted to suitably support the various devices, driving mechanism, a pair of alternately, intermittently movable belts or conveyers, two sets of can 45 head or other article feeding devices for supplying or placing the articles on the conveyers, a single set of spraying or coating devices adapted to alternately spray the articles on first one of the conveyers and 50 then on the other; drying conveyers to receive the can heads or other articles from the first named conveyers after the articles have been treated, and suitable mechanism for automatically operating the conveyers, feeders and sprayer at proper intervals.

In the drawing forming a part of this specification, Figure 1 is a plan view of a machine embodying my improvements, the tank being removed to more clearly illustrate the parts. Fig. 2 is an end view of 60 the structure shown in Fig. 1. Fig. 3 is a sectional view, taken on the line 3—3 of Fig. 1. Fig. 4 is a sectional view, taken on the line 4—4 of Fig. 1. Fig. 5 is an end view of the machine, taken at the opposite 65 end to that shown in Fig. 2, and Figs. 6, 7, 8 and 9 are detail views, upon enlarged scales, of the article feeding device, the valve mechanism, spraying nozzle and the air controlling valve, respectively. 70

In the drawings, 10 denotes the frame adapted to suitably support the various parts of the mechanism, and over which runs a pair of parallelly arranged endless conveyers A, A, over each of which at the 75 front end of the machine is placed a set of can head or other article feeding devices B, B, and toward the rear of the machine is located a spraying device C, the same being adapted to coöperate alternately with the 80 articles on each of the conveyers A, A, and, as will be noticed from Fig. 1, a space is provided between the feeding devices B and the spraying device C, where the operator may observe the articles which have been 85 placed upon the conveyers. Each of the conveyers runs over suitable pulleys provided on the machine, and is driven alternately and intermittently by the following mechanism: a power driving shaft 11 90 is mounted at the front end of the machine and is driven from any suitable source of power, as by means of a pulley 12, and has keyed thereto a wide gear 13 with which meshes a narrow gear 14, the latter being 95 provided with a hub 15 having clutch faces 16 on each end thereof, said gear 14 being loosely and slidably mounted on a supporting shaft 17. Each of the pulleys at this 100 end of the machine which support and drive the conveyers A, A, is loosely mounted on the shaft 17 and is provided with a clutch face 18 adapted to coöperate with its corresponding clutch face 16. Each of the 105 conveyers A, A is provided with a plurality of spaced trips or cams 19, the same being so arranged that they engage alternately, opposite ends of a slide bar 20 and push the latter alternately from one side to the other. Pivoted to this slide bar 20 is a lever 110

21, having pivoted at its opposite end a shipper lever 22, having forked arms 23, 23, which engage the gear 14, and as will be obvious, shift the latter so as to engage 5 alternately the clutch faces 18, 18. The slide bar 20 is provided at each end thereof with a pivoted member 24, in order to allow the ends of the bar to clear a trip or cam 19 on one conveyer when the bar is operated 10 from a trip or cam on the opposite conveyer. In order to retain the gear 14 and the clutch faces 16, 16 connected therewith in proper position after the shifting operation has taken place, I mount a spring pressed pin 25 in the end of the machine, and provide the latter with a beveled end adapted to co-operate with a V-shaped ring 26 formed on the hub 15.

Each set of feeding devices B is operated 15 at the proper time by means of the trips or cams 19 by a reciprocating slide 27 having a roller at the end thereof adapted to be engaged by the trips or cams, and having pivoted thereto at its opposite end a bell crank 28, the latter being connected by means of a link 29 to a common connecting rod 30, pivotally secured to a plurality of lever arms 31 of each of the feeding mechanisms, the bar 30 having secured thereto at one end a retracting spring 130 secured at its opposite end to a stationary part of the frame. Each of the article feeding mechanisms, as more clearly shown in Figs. 4 and 6, consists of a stationary stack holder 32, suitably secured to the bed of the machine, and having pivoted thereto two sets of diametrically arranged feed fingers 33, and having also mounted at the bottom thereof and adapted to oscillate, a cam disk 34, the same being provided with a plurality of cam slots 35, in which move pins 36 connected to the feed fingers 33. The lever arm 31 is formed integral with the disk 34, and as will be obvious, each time 40 the latter is oscillated, the fingers 33 will be moved in and out alternately and will alternately support the stack of can heads or other articles and cut out the bottommost article at each complete oscillation of the disk 34.

After the articles have been discharged 45 from the feed devices B onto the chucks 37 of the conveyer, the articles are next transferred to a position beneath the spraying or coating device C. The latter comprises a plurality of spraying heads 38, 38, the number of said heads corresponding to the number of articles fed by the feed devices B, and each of said heads 38 comprises a cylindrical portion 39, provided with an inwardly extending nozzle 40, the latter having a plurality of radially arranged perforations 41 through which the lacquer or other liquid is adapted to be projected, and the cylindrical member 39 is preferably provided

with a plurality of plugs 42, by means of which access may be had to the perforations 41 to clean the same if necessary. Each of the spraying heads is also provided with an air pipe 43, the same terminating slightly 70 above the perforation 41, and as will be obvious, is adapted to scatter or spread the liquid as the same comes through the perforations 41. Each of the spraying nozzles is also connected to a supply tank 44, as by 75 means of a flexible tube 45, and each of the air pipes 43 connects at its top with a common air distributing pipe 46, the latter at one end being connected as by means of a flexible tube 47, with any suitable source 80 of supply of compressed air. The spraying nozzles or coating devices 38 are mounted on a pair of oscillating arms 48, the latter being secured to a rock shaft 49 and operated by means of a segmental gear 50, which 85 co-operates with a similar segmental gear 51, the latter being operated from a cam disk 52 secured to a longitudinally arranged shaft 53, having a bevel gear 54 at one end thereof, meshing with a corresponding bevel gear 55 secured to the end of the power shaft 11. The cam on the cam disk 52 is so arranged that the spraying devices are moved alternately from one side of the machine to the other and have a period of rest 90 at the end of each movement or oscillation 95 of the spraying devices in order to allow the latter sufficient time in which to coat or spray the articles being treated.

In the supply tank 44 is mounted a reciprocating slide valve 56 (see Fig. 7) which is provided with a plurality of perforations 57 adapted to register with the tops of the pipes 45. Said valve 56 is operated from one side to the other by means of a pair 100 of levers 58, 58, the latter being keyed to the upper ends of rock shafts 59, 59, which are rocked alternately by means of arms 60, 60, secured thereto at their lower ends, said arms 60, 60 being moved or rocked by means 105 of the trips or cams 19, 19. The slide valve 56 is so operated that the perforations 57 therein are moved first from one side of the tops of the pipes 45 to the other, and the liquid is supplied to the spraying nozzles 110 during the period when the perforations in the tops of the pipes register.

In order to regulate the flow of the compressed air to the nozzles 38, 38, a valve is placed in the supply pipe 47 and is operated by means of a lever arm 61, having pivotally connected thereto a link 62, the latter being pivoted to one arm of a bell crank 63, and the opposite end of which is operated as by means of cams 64 on the end 120 of one of the levers 48. A spring 65 is also provided for returning the valve controlling mechanism to its normal position during the time that the spraying device C is being moved from one side of the machine 125 130

to the other. After the articles have been coated or sprayed, the conveyers are again operated and the articles dropped from the conveyers A, A, at the end of the machine 5 to drying conveyers D, D, which transfer the treated articles to a drying oven or other suitable mechanism, as desired.

The operation is as follows: Only one of the conveyers A, A moves at a time, and 10 while this conveyer is moving, one of the trips or cams 19 engages the end of the sliding bar 27 and operates to feed the articles to the other conveyer, which at the time, is stationary. As the conveyer moves, the same 15 trip or cam will engage the rock lever 60 and operate the valve in the supply tank and set the valve mechanism so that the same will be operated by the other conveyer when the latter is moved. Prior to the conveyer 20 coming to rest, the spraying device C is moved from a position over the stationary conveyer to the conveyer which is now moving preparatory to spraying the articles on the moving conveyer when the latter is 25 brought to rest. At this time another cam or trip 19 operates the slide bar 20 and the shifting mechanism for the gear and brings the moving conveyer to rest, and starts the opposite conveyer into motion. In this way 30 the two conveyers and the various mechanisms are operated intermittently and alternately so long as the power shaft 11 is in motion.

As will be apparent to those skilled in the 35 art, many changes may be made in the various parts and details of the machine without departing from the spirit of the invention, such, for instance, as the substitution of different types of can head or other article 40 feeding devices for those which I have shown and described, and also the substitution of other forms of sprayers, conveyers and driving mechanisms, and all such changes and variations are contemplated as fall within 45 the scope of the claims appended hereto.

I claim:—

1. In a machine for coating articles, in combination: a continuously operating driving mechanism, conveyers having means for 50 holding said articles and adapted each to have intermittent movement alternating with the similar movement of the other conveyer; means whereby each conveyer causes the other conveyer to be connected with said driving mechanism and causes itself to be disconnected; automatic means actuated from said driving mechanism for feeding said articles to the conveyers, said feeding mechanism for one conveyer being operative 55 when the feeding mechanism for the other conveyer is inoperative; and means for coating said articles.

2. In a machine of the character described, in combination, intermittently, movable conveyers, a set of article feeding mechanisms

comprising a plurality of members each adapted to feed an article, one at a time, and means for treating the articles, said means being movable alternately from a position over one of said conveyers to a position over 70 the other.

3. In a machine of the class described, in combination, a frame, conveyers mounted thereon, article feeding devices and means for coating the articles, said means being 75 movable alternately to a position adjacent each other of said conveyers.

4. In a machine of the character described, in combination: a pair of parallelly arranged, alternately, intermittently movable 80 conveyers; a battery of article feeding devices located above each of said conveyers; and means for automatically operating each battery of said devices, the means for operating one set of devices being actuated by 85 the conveyer over which the other battery of said devices is located, substantially as specified.

5. In a machine of the class described, in combination a pair of endless conveyer belts 90 having alternately intermittent movement, article feeding devices for each of said conveyers and means for spraying the articles on the conveyers, said means comprising a plurality of spraying nozzles movable 95 from a position over one of the conveyers to a position over the other of the conveyers, each of said nozzles being provided with a pipe connection to a supply tank, and automatically operated valve mechanism for regulating the supply to the nozzles. 100

6. In a machine of the character described, in combination: two spaced, movable conveyers each adapted to convey can ends or like articles; and a spraying device movable 105 alternately to operative position adjacent each of said conveyers whereby the same spraying device is adapted to treat all the articles on both conveyers, substantially as specified. 110

7. In a machine of the character described, in combination: two spaced, alternately, intermittently movable conveyers adapted to carry can ends thereon; and a spraying device movable alternately to operative position adjacent each of said conveyers, the spraying device being brought to operative position adjacent a conveyer during a period of rest thereof, substantially as specified. 115

8. In a machine for coating can heads, in combination: an endless conveyer arranged to hold at intervals a predetermined number of successive can heads; means for actuating the conveyer intermittently for a distance equal to that occupied by said predetermined number of successive can heads; means for feeding such number of can heads at one time to the conveyer while it is at rest; means for coating said number of can heads at one time while the conveyer is at 120 125 130

rest, the coating means being arranged at a distance from the feeding means a space equal to said number of can heads, whereby an intermediate observing station is provided where the can heads to be treated may be observed while at rest; means for actuating said feeding means intermittently and while the conveyer is at rest; and devices for causing the operation of the coating means intermittently and while the conveyer is at rest.

9. In a machine for coating can heads, in combination: endless conveyers arranged side by side and each adapted to hold at intervals a predetermined number of successive can heads; feeding means for each conveyer, for feeding such predetermined number of can heads at one time to the conveyer while it is at rest; coating means for coating the said number of can heads at one time on each conveyer while the conveyer is at rest; and means whereby the conveyers alternately cause the actuation of each other intermittently and the intermittent operation of the feeding and coating means.

10. In a machine for coating can heads, in combination: carriers arranged side by side and having means for holding articles to be coated; coating devices arranged to act alternately first on the articles held on one of the said carriers and then on the articles held on the other of the said carriers; means for supplying the coating devices with coating to be applied to the said articles; means for shifting the coating devices from one carrier to the other; and means whereby the carriers are actuated intermittently and alternately.

11. In a machine for coating can heads, in combination: carriers arranged side by side and having means for holding articles to be coated; coating devices arranged to act alternately first on the articles held on one of the said carriers and then on the articles held on the other of the said carriers; means for supplying the coating devices with coating to be applied to the said articles; means for shifting the coating devices from one carrier to the other; and means whereby the carriers are actuated intermittently and alternately; each carrier being provided with means whereby it causes the actuation and advance of the other carrier at a predetermined time and for a predetermined distance.

12. In a machine for coating can heads, in combination: carriers arranged side by side and having means for holding articles to be coated; coating devices arranged to act on the said articles; a coating supply arranged to feed coating to said devices; article feeders arranged to feed articles first to one carrier and then to the other; means for actuating the said carriers intermittently and alternately; means for causing a correspond-

ing intermittent and alternate operation of the article feeders; and means for causing the intermittent delivery of coating first to the articles on one conveyer and then to the articles on the other conveyer, each conveyer being advanced in the interval when the coating is not being delivered; the coating means being movable from one conveyer to the other.

13. In a machine for coating can heads, in combination: carriers arranged side by side and having means for holding articles to be coated; coating devices arranged to act on the said articles; a coating supply arranged to feed coating to said devices; article feeders arranged to feed articles first to one carrier and then to the other; means for actuating the said carriers intermittently and alternately; means for causing a corresponding intermittent and alternate operation of the article feeders; and means for causing the intermittent delivery of coating first to the articles on one conveyer and then to the articles on the other conveyer, each conveyer being advanced in the interval when the coating is not being delivered; the coating means being movable from one conveyer to the other; and the flow of coating being controlled by such movement.

14. In a machine for coating can heads, in combination: an endless conveyer arranged to hold at intervals a predetermined number of successive can heads; means for actuating the conveyer intermittently for a distance equal to that occupied by said predetermined number of successive can heads; means for feeding such number of can heads at one time to the conveyer while it is at rest; means for coating said number of can heads at one time while the conveyer is at rest, the coating means being arranged at a distance from the feeding means a space equal to said number of can heads, whereby an intermediate observing station is provided where the can heads to be treated may be observed while at rest; the said coating means being movable to operating position when the conveyer is at rest, and the flow of coating being controlled by such movement.

15. In a machine for coating articles, in combination: conveyers having alternate intermittent movement for a distance greater than the space occupied by one article, so as to advance said articles in groups, driving mechanism for said conveyers whereby they are alternately advanced for the said distance, means for placing articles on said conveyers in groups, and means for treating a plurality of or group of articles on said conveyers alternately while a group of articles on the other conveyer is advanced.

16. In a machine for coating articles, in combination: conveyers having alternate intermittent movement, driving mechanism

for said conveyers arranged to give them the said movement, means for placing articles on said conveyers, and means shiftable from one conveyer to the other for treating said articles.

17. In a machine of the character described, in combination: a pair of conveyers alternately and intermittently movable; means shiftable from one conveyer to the other for 10 treating articles on said conveyers; and a driving mechanism for said conveyers, said mechanism including shiftable means adapted to alternately and operatively connect the conveyers with said driving mech- 15 anism.

18. In a machine for coating can heads, in combination: carriers arranged side by side and having means for holding articles to be coated, coating devices arranged to act on

the said articles, a coating supply shiftable 29 from one carrier to the other and arranged to feed coating to said devices, article feeders arranged to feed articles first to one carrier and then to the other, means for actuating the said carriers intermittently and 26 alternately, means for causing a corresponding intermittent and alternate operation of the article feeders, and means for causing the intermittent delivery of coating first to the articles on one conveyer and then to the 29 articles on the other conveyer, each conveyer being advanced in the interval when the coating is not being delivered.

CHARLES W. GRAHAM.
